BULK MATERIAL DELIVERY TRUCK

Charles G. Eisenberg, Jr., Wauwatosa, Wis., assignor to The Heil Co., Milwaukee, Wis., a corporation of Wisconsin

Application August 8, 1938, Serial No. 223,621

8 Claims. (Cl. 298—7)

The present invention relates to improvements in the art of transporting materials in bulk, and relates more specifically to improvements in the construction and operation of bulk material delivery trucks or vehicles.

An object of the invention is to provide an improved bulk material haulage and delivery body which is compact and durable in construction, and from which the load may be conveniently withdrawn and properly directed.

In the transportation and delivery of granular material such as coal in bulk, it frequently becomes desirable to simultaneously carry several segregated quantities or grades of the commodity in a common carrier body, and to be able to deliver the segregated charges to either side of the vehicle at the will of the delivery man. In some cases it is preferable to spout the material directly from the confining and transporting body directly into a receiving bin, and in other cases it is desirable to withdraw successive batches such as basket-loads from the body compartments. Numerous relatively complicated spouting devices for permitting such independent and diversified withdrawal of charges of granular material from vehicle bodies, have heretofore been proposed and used commercially, but all of the prior assemblages have proven more or less objectionable either because they lacked requisite simplicity and were therefore apt to become inoperative, or because they could not withstand the abuse and hard usage to which such apparatus is normally subjected, or because they permitted undesirable bridging of material such as mine run coal, or for many other reasons.

It is therefore an object of my present invention to provide an improved spouting assemblage for coal haulage trucks or the like, which is extremely simple in construction and highly effective in use.

A more specific object of the present invention is to provide an improved carrier body and spouting system therefore, wherin material may be delivered to either side and from any portion of the body without danger of having the material bridge over the delivery openings.

Another specific object of my invention is to provide a new and useful material delivery system for truck bodies, which can be conveniently manipulated by a novice, to effect either continuous or batch delivery of the load, and which will not interfere with normal raising or lowering of the carrier body.

A further specific object of my present improvement is to provide a durable and inexpen-

sive delivery mechanism for vertically movable truck bodies having oppositely inclined bottom walls, wherein the entire load may be quickly and effectively delivered from either side of the body, even if the material is of a bridging type such as moist mine run coal containing a large proportion of fines mixed with larger lumps.

These and other specific objects and advantages will be apparent from the following detailed description.

A clear conception of the several improved features and of the construction and operation of one commercial embodiment of my invention, may be had by referring to the drawing accompanying and forming a part of this specification wherein like reference characters designate the same or similar parts in the several views.

Fig. 1 is a transverse vertical section through the lower portion of a truck body having my improved material delivery mechanism applied thereto, and showing a short basket filling spout associated with one of the delivery chutes;

Fig. 2 is a fragmentary side elevation of one of the material delivery chutes and of the special basket filling spout; and

Fig. 3 is a rear and side perspective view of a complete truck and carrier body assembly, showing the body elevated to maximum height and relatively long delivery spouts applied to one of the improved adjustable chutes.

While the invention has been illustrated and described herein as being especially applicable to vertically adjustable coal delivery truck bodies of the multiple compartment hopper bottom type, it is not the intent to unnecessarily limit the scope or utility of the improvement by virtue of such specific embodiment.

Referring to the drawing and more particularly to Fig. 3, the vehicle or truck 5 has a frame 6 provided with rigid upright corner guides 7, 40 mounted thereon; and a carrier body 8 is provided with four upright guide bars 9 which coact with the frame guides 7 and is vertically movable relative to the frame 6 by means of upright hydraulic hoists 10, in a well known manner. 45 The body 8 is provided with longitudinally extending side beams 11 connecting the front and rear guide bars 9, and the beams 11 are adapted to rest directly upon the side beams of the frame 6 when the body 8 is in lowermost position as 50 when the truck 5 is transporting the load.

The carrier body 8 may be divided into two or more segregated material receiving and confining compartments, by means of partitions 12 and has oppositely inclined bottom walls 13 to which 55

the beams 11 are attached and which intersect along a horizontal line 14, see Figs. 1, 2 and 3. Each of the inclined bottom walls 13 within each of the several compartments, is provided with a material delivery opening 15 extending upwardly from the intersection line 14, and each opening 15 is provided with a slidable closure 16 which is manipulable by a lever 17 acting through a link 18 guided in a slot in the adjacent side beam 11. Each material delivery opening 15 is moreover provided with side and bottom apron walls 19, 20 respectively secured to the exterior of the adjacent bottom wall 13, and the closures 16 of the several openings 15 may obviously be independently opened or closed by manipulation of the levers 17 from the sides of the truck 5. Lower and upper rails 21, 22 respectively are permanently and rigidly attached to the body 8 and extend throughout the length thereof. The lower rails 21 which are formed integral with each other, are secured to the apron walls 20 and to the lowermost portion of the carrier body 8, and the upper rails 22 are attached to the lower outer portions of the side apron walls 19. A material delivery chute 23 is slidably suspended from each set of rails 21, 22 by means of lower and upper beads 24, 25 secured to each chute, and each of the chutes 23 is provided with a handle 26 for facilitating sliding of the chutes 30 along the rails. Each chute 23 is of such size that it may be brought into registry with the apron walls 19, 20 of the adjacent openings 15, and when so positioned, the corresponding walls 13, 20 and the lower wall 27 of the delivery chute 35 will be in approximate alignment with each other.

The chutes 23 may also be provided with end pins 28 and with medial latch hooks 29 for effecting detachable attachment of short or long spouts 30, 31 thereto. As illustrated in Figs. 1 and 2, the short spout 30 is provided with end hooks 32 which are cooperable with the end pins 28 of the chutes 23, and the latch hooks 29 of the chutes 23 are cooperable with a transverse retainer 33 secured to the upper end of the spout 30. The long spout 31 shown in Fig. 3, may be provided with a similar attaching means, and the short spout 30 is preferably additionally provided with a swing gate 34 secured thereto by pivot pins 35 and having a manipulating handle 36 as illustrated in Figs. 1 and 2. Additional spouts 31 of various lengths may also be provided so as to permit spouting of the material a considerable distance from the truck 5, and the spouts 30, 31 may be hung at the rear of the assemblage when not in use. Most of the parts of the material transporting and delivery assemblage may be formed of sheet metal riveted or welded together, and the rails 21, 22 may be provided with suitable lubricant such as grease to insure easy sliding of the chutes 23 therealong.

During normal use of the improved assemblage, while the body 8 is being loaded with material and when the load is being transported from place to place, the body is lowered so as to cause the side beams 11 to engage the lower frame 6, and the delivery chutes 23 are then confined between and are protected by the side beams of the frame 6. All of the openings 15 are in closed position as shown in Fig. 1, and the levers 17 are so formed that they will clear the side beams of the frame 6 and will permit beams 11 to rest upon the frame 6 without obstruction.

When it becomes desirable to discharge the contents of one of the compartments formed by

the partitions 12, such delivery may obviously be effected from either side of the vehicle or truck 5. The body 8 may then be elevated with the aid of hydraulic hoists 10 to the position shown in Fig. 3, whereupon the chute 23 should be positioned adjacent the opening 15 from which delivery of material is to be effected. An appropriate delivery spout 30, 31 should then be applied to the delivery chute 23, and if the load is to be delivered in successive batches into baskets or other receptacles, a short spout 30 will be utilized, whereas for direct delivery of the load to a bin or manhole would necessitate the use of one or more long spouts 31 as illustrated in Fig. 3. After the chute 23 and directing spout have been properly associated with the opening 15 through which delivery is to be effected, the corresponding levers 17 may be manipulated to withdraw the closure plate 16 more or less depending upon the desired rate of delivery. Such uncovering of the opening 15 will cause the material to gravitate through the opening and along the apron wall 20 and bottom 27 of the delivery chute, and the material will thereafter flow by gravity along the spout 30 or 31 which is attached to the chute 23. By virtue of the fact that the openings 15 extend upwardly from the lowermost portion of the bottom walls 13, that is, from the intersection line 14, the entire charge from each compartment may obviously be readily delivered from such compartment by gravity, and the opposite inclination of the bottom walls 13 toward the intersection line 14 will obviously prevent material from bridging over the discharge openings 15. When the desired quantity of material has been discharged from any of the compartments, the closure plate 16 may again be moved to closed position by manipulation of the corresponding lever 17, and further delivery of material will then cease. It is also to be noted that delivery of the material may be effected from either side of the truck 5 and from any of the several compartments, independently of all others, and the chutes 23 are conveniently slidable into a position of cooperation with any of the corresponding discharge openings 15.

From the foregoing detailed description it will be apparent that my present invention provides an improved structure and system for effecting universal delivery of material from a multiple compartment truck body, in any desired direction and from any desired compartment of the body. Such delivery may be rapidly and conveniently effected by merely properly positioning the discharge chutes 23 and by subsequently manipulating the closure plates 16, and in view of the fact that the chutes 23 are of relatively light but durable construction, they may be conveniently positioned as desired. These chutes 23 are at all times protected against possible damage and the material directing spouts 30, 31 may be quickly attached thereto or removed therefrom, and the use of short spout 30 provides controllable means for permitting delivery of batches of material to baskets or similar receptacles. The formation of the bottom walls 13 and the provision of openings 15 therein extending upwardly from the intersection line 14 of the walls 13, is of considerable importance since it not only makes it possible to deliver all of the material by gravity, but such formation also prevents bridging of the material across the openings 15. The attendant is therefore able to deliver all portions of the load without crawling to the top of the body 8 and breaking up the charge which would otherwise tend to

bridge across the discharge openings. The entire assemblage is obviously simple and compact in construction besides being durable and readily manipulable, and the invention has proven highly 5 successful in actual commercial use.

It should be understood that it is not desired to limit this invention to the exact details of construction or to the precise mode of use, herein shown and described, for various modifications 10 within the scope of the claims may occur to persons skilled in the art.

I claim:

1. In combination, a material confining and transporting body having oppositely inclined intersecting bottom walls each provided with several material delivery openings extending upwardly therealong from the line of intersection, and a discharge chute movable horizontally along the exterior of each of said walls and being interchangeably communicable with the corresponding 15 openings, each of said discharge chutes having its bottom in approximate alignment with the opposite bottom wall of the body.

2. In combination, a material confining and transporting body having oppositely inclined intersecting bottom walls each provided with several material delivery openings extending upwardly therealong from the line of intersection, a discharge chute movable horizontally along 20 the exterior of each of said walls and being interchangeably communicable with the corresponding openings, each of said discharge chutes having its bottom in approximate alignment with the opposite bottom wall of the body, and an independently operable closure for each of said openings.

3. In combination, a material confining and transporting body having oppositely inclined bottom walls each provided with several material delivery openings extending upwardly therealong 40 from the lowermost edge of the wall, rails associated with said body and extending externally along each of said walls, and a discharge chute movable horizontally along each of said rails and being interchangeably communicable with said 45 openings, each of said discharge chutes having its bottom in approximate alignment with the opposite bottom wall of the body.

4. In combination, a material confining and transporting body having oppositely inclined bottom walls each provided with several material delivery openings extending upwardly therealong from the lowermost edge of the wall, rails associated with said body and extending externally along each of said walls, a discharge chute movable horizontally along each of said rails and being interchangeably communicable with said 55 openings, each of said discharge chutes having its

bottom in approximate alignment with the opposite bottom wall of the body, and an independently operable closure for each of said openings.

5. In combination, a material confining and transporting body having oppositely inclined intersecting bottom walls each provided with several material delivery openings extending upwardly therealong from the line of intersection, partitions dividing said body into a series of segregated compartments, rails extending along 10 said body externally of said walls, and a discharge chute movable horizontally along the exterior of each of said walls and being interchangeably communicable with said compartments through the corresponding delivery openings thereof, each of said discharge chutes having its bottom in approximate alignment with the opposite bottom wall of the body.

6. In combination, a material confining and transporting body having oppositely inclined intersecting bottom walls each provided with several material delivery openings extending upwardly therealong from the line of intersection, partitions dividing said body into a series of segregated compartments, rails extending along said body externally of said walls, a discharge chute movable horizontally along the exterior of each of said walls and being interchangeably communicable with said compartments through the corresponding delivery openings thereof, each of 15 said discharge chutes having its bottom in approximate alignment with the opposite bottom wall of the body, and an independently operable closure for each of said openings.

7. In combination, a transportable frame having spaced side beams, a hopper movable toward and away from said frame and having side beams cooperable with said frame beams when said hopper is in lowermost position, said hopper having oppositely inclined lower walls provided with 40 material delivery openings extending upwardly therealong, and delivery chutes slidably along and carried by said bottom walls within the space between said beams.

8. In combination, a transportable frame having spaced side beams, a hopper movable toward and away from said frame and having side beams cooperable with said frame beams when said hopper is in lowermost position, said hopper having oppositely inclined lower walls provided 45 with material delivery openings extending upwardly therealong, delivery chutes slidably along and carried by said bottom walls within the space between said beams, and independently manipulable closures for said openings.

CHARLES G. EISENBERG, JR.
